(57) **CLAIM**

We claim the ornamental design for a probe for ultrasound diagnostic apparatus, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a probe for ultrasound diagnostic apparatus showing our new design;

FIG. 2 is a front-side elevational view thereof;

FIG. 3 is a rear-side elevational view thereof;

FIG. 4 is a left-side elevational view thereof;

FIG. 5 is a right-side elevational view thereof;

FIG. 6 is a top-side elevational view thereof; and,

FIG. 7 is a bottom-side elevational view thereof.

The broken lines are includes for the purpose of illustrating portions of the probe for ultrasound diagnostic apparatus that form no part of the claimed design. The dot-dash lines show the boundaries of the claimed subject matter and form no part of the claimed design.
